UNITED STATES PATENT OFFICE.

PHILIP S. BLILER, OF MYERSBURG, MONTANA, ASSIGNOR OF ONE-HALF
TO JAMES N. ENNIS, OF MYERSBURG, MONTANA.

TENT-PIN.

No. 798,654.

Specification of Letters Patent.

Patented Sept. 5, 1905.

Application filed April 3, 1905. Serial No. 253,651.

To all whom it may concern:

Be it known that I, PHILIP S. BLILER, of Myersburg, in the county of Park and State of Montana, have invented certain new and 5 useful Improvements in Tent-Pins, of which the following is a specification.

The object of this invention is to provide a pin for tents and for tethering stock, which may be easily anchored securely in the ground. 10 The invention is exemplified in the structure hereinafter described, and it is defined in the appended claims.

In the drawings forming part of this specification, Figure 1 is an elevation of a pin embodying my improvements. Fig. 2 is a longitudinal section of the pin, showing the anchor-flukes extended into the earth; and Fig. 3 is a detail of the cap used on the upper end of the pin while driving the pin into the 20 ground.

The body of the pin is in the form of a tube 1, and the point 2, which is solid, is secured in the lower end of the tube. The cap 3 has the annular contraction 3^a, which fits in the 25 upper end of the tube. Side openings 4 for the protrusion of the anchor-flukes are formed in the tube at the conjunction of the point therewith, and a slot 11 is formed in the upper end of the tube for a purpose to be hereinafter explained.

The flukes 8 are pivoted at their inner ends to the lower end of a rod 6, and their lower protrudable ends rest normally on inclines formed by the upper end of point 2. The 35 rod 6 extends through a bearing 10, and at its upper end it is pivotally connected with a rod 5, as shown at 7. A strap 12, secured to the outer surface of the tube, provides a hitch for a tent-rope or for a tethering-line.

With the parts in the positions shown in Fig. 1 the pin is ready for insertion into the ground. After the pin has been driven to the required depth by force applied to the cap the cap is removed, the rod 5 is swung

into alignment with rod 6, and the flukes are 45 spread into the earth by force applied to the upper end of the rod. After the flukes are spread sidewise, as shown in Fig. 2, the rod 5 may be returned to slot 11, through which it will extend obliquely, and the cap 50 may be replaced.

The slot 11 receives the rod 5, while said rod is swung out of the way of the cap. The removable cap permits the rod 5 to be swung into position to spread the flukes, and the 55 joint 7 makes the different positions of the rod 5 possible. The bottom of slot 11 forms a fulcrum upon which rod 5 may swing as a lever in retracting the flukes preparatory to withdrawing the pin. 60

When the flukes are spread into the earth, the pin is securely anchored. The spreading of the flukes is effected by force applied in a direction tending to force the pin farther into the earth, and the jointing of the fluke-rods 5 65 and 6 enables the operations attending the use of the pin to be readily performed.

Having thus described my invention, I claim as new and desire to secure by Letters Patent—

A tent-pin comprising a tubular body having a slot in its upper end and a pair of oppositely-placed openings in its lower end, a point for the lower end of the pin, a pair of anchor-flukes pivotally conjoined in the tube with their ends in the side openings thereof, 75 a non-swingable rod connected pivotally with the flukes and held slidably in the center of the tube, a swingable rod pivoted to the upper end of the non-swingable rod and adapted to swing into the slot in the upper end of the 80 tube, and a removable cap for the upper end of the tube, substantially as set forth.

In testimony whereof I sign my name in the presence of two subscribing witnesses.

PHILIP S. BLILER.
